(57) CLAIM

The ornamental design for a solid-state lighting tube lamp, as shown and described.

DESCRIPTION

FIG. 1 is a front view of a solid-state lighting tube lamp showing our new design;

FIG. 2 is a back view thereof;

FIG. 3 is a top view thereof;

FIG. 4 is a bottom view thereof;

FIG. 5 is a left side view thereof; and,

FIG. 6 is a right side view thereof.

The broken lines in the drawings illustrate portions of the solid-state lighting tube lamp which form no part of the claimed design.
